UNITED STATES PATENT OFFICE.

STEPHEN S. KRAYER, OF ST. LOUIS, MISSOURI.

MEANS FOR SUPPLYING EXPLOSIVE MIXTURE TO EXPLOSIVE-ENGINES.

1,051,122.

Specification of Letters Patent. Patented Jan. 21, 1913.

Application filed November 18, 1911. Serial No. 661,000.

To all whom it may concern:

Be it known that I, STEPHEN S. KRAYER, a citizen of the United States of America, and resident of the city of St. Louis and State of Missouri, have invented certain new and useful Improvements in Means for Supplying Explosive Mixture to Explosive-Engines, of which the following is a full, clear, and exact description, reference being had to the accompanying drawings, forming part of this specification.

My invention relates to a device intended to be used as an auxiliary to the main carbureter and explosive member supplying device of an explosive engine, through the medium of which an initial quantity of explosive mixture may be delivered to the cylinder, or cylinders, of the engine, for the purpose of providing for the engine being started without resorting to the usual "cranking" operation.

Figure I is a view partly in elevation and partly in section, illustrating my improvement. Fig. II is an inverted plan view of the air injector located in the auxiliary carbureter shell. Fig. III is an elevation of a modified form of air injector.

In the accompanying drawings:—A designates the cylinders of an explosive engine. I have shown four of such cylinders, but it will be obvious that my improvement may be used in connection with any number of cylinders. Explosive mixture is delivered to said cylinders through branch pipes B leading from a manifold C, common to all of the branch pipes.

D designates a main carbureter that is placed in communication with the manifold C by a conducting pipe E, through which explosive mixture generated in an ordinary manner may be delivered to the manifold, and therefrom to the engine cylinders. The main carbureter has associated with it a float chamber F, containing a float G, through the medium of which the level of hydrocarbon oil in the main carbureter is controlled.

No invention *per se* is herein claimed for the parts thus far described, they all being common to old forms of devices for creat-

ing and supplying explosive mixtures to explosive engines.

1 designates the shell of my auxiliary carbureter, between which and the float chamber F communication is established by a connecting pipe 2 that provides for the delivery of hydrocarbon oil from said float chamber to the interior of the auxiliary carbureter shell. The float G controls the level of hydrocarbon oil in the auxiliary carbureter shell.

3 designates an explosive mixture conducting pipe leading from the auxiliary carbureter shell to the manifold C, and through which explosive mixture may be conducted to said manifold to be distributed therefrom to any one or more of the engine cylinders in which the parts are in proper positions to receive a charge of explosive mixture.

4 designates an air conducting pipe through which air under pressure may be led from any source of supply to the interior of the carbureter shell, 1. The pipe 4 communicates with an injector 5 comprising a coil having perforations therein, the perforations being preferably minute in size. The air injector coil is disposed horizontally in the carbureter shell 1 near the bottom of said shell, and its perforations are preferably in the bottom of said coil, in order that air under pressure delivered into the injector and discharged therefrom may be directed downwardly in the hydrocarbon oil to thereafter rise in the oil while becoming saturated with the volatile elements of the oil.

6 is a horizontal screen extending transversely of the auxiliary carbureter shell above the level of the hydrocarbon oil in said shell, and through which the explosive mixture of air saturated with the volatile elements or fumes of said oil pass before entering into the conducting pipe 3 to pass therefrom to the engine cylinders that are to be supplied with explosive mixture.

At the point of communication between the conducting pipe E leading from the main carbureter and the manifold C is a check valve 7 that opens inwardly within

said manifold and is normally held from its seat by a spring 8. This valve is adapted to be closed to shut off communication between the manifold and the main conducting pipe E when explosive mixture is being generated in my auxiliary carbureter, and being delivered to the engine cylinders A. To provide for the automatic closing of said valve, I arrange within the manifold C a T-shaped nozzle 9 directed at one end toward the check valve 7, and at the other end toward the outlet from the manifold. It will be obvious that this construction may provide for the delivery of explosive mixture toward and against the check valve with sufficient pressure to move the valve to its seat against the action of the spring 8, thereby providing the passage of the explosive mixture delivered from the auxiliary carbureter to the conducting pipe of the main carbureter.

10 and 11 are cut off valves that respectively control the flow of hydrocarbon oil through the pipe 2 and air under pressure through the pipe 4. These valves are connected in common to an operating rod 12, by which they may be actuated in unison, and the valves are so arranged that when one of them is opened, the other is closed.

In Fig. III, I have shown a modification 30 of the air injector in the shell of my auxiliary carbureter, this modification comprising a rose 5' that may be used in lieu of the coil 5.

In the practical use of my improvement, 35 the operation is as follows: Assuming that the auxiliary carbureter shell 11 contains a supply of hydrocarbon oil, as illustrated in the drawings, an initial supply of explosive mixture is delivered to the engine cylinders by opening the air pipe valve 11 through the medium of the operating rod 12, which may be manipulated in any suitable manner, and the operation of which causes the valve 10, controlling the outlet 2, to be closed. Upon 40 the opening of the valve 11, air under pressure is admitted to the injector 5 and discharged therefrom into the hydrocarbon oil in which the injector is submerged. The air being discharged from the injector under 45 pressure circulates rapidly in the oil and becomes impregnated with the volatile and explosive elements of the oil while passing upwardly therethrough. As the saturated air, or what is then an explosive mixture, rises 50 above the surface of the hydrocarbon oil, it passes through the screen 6 and is delivered by the conducting pipe 8 into the manifold C and finally to the engine cylinders that are to be supplied with explosive mixture 55 preparatory to ignition of the mixture for the purpose of placing the engine initially in operation preparatory to the supply of explosive mixture thereto from the main carbureter. When sufficient supply of ex-

plosive mixture has been created in the auxiliary carbureter and delivered to the engine cylinders to start the engine, the operating rod 12 is manipulated for the purpose of shutting off the flow of air under pressure through the pipe 4 and reestablishing communication between the float chamber F and the auxiliary carbureter shell by opening the valve 10, in order that the supply of hydrocarbon oil in said shell may be replenished.

I claim:—

1. The combination with an explosive engine and a main carbureter for supplying explosive agent to said engine, of a starting device comprising an auxiliary carbureter shell having communication with said main carbureter and with a cylinder of said engine, an air injector submerged in the explosive agent contents of said shell, means for delivering air under pressure to said injector, and simultaneously operable means whereby the passageway in said air delivery means is opened and the passageway between said auxiliary and main carbureters is closed.

2. The combination with an explosive engine, and a main carbureter for supplying explosive agent to said engine, of a starting device comprising an auxiliary carbureter shell having communication with the cylinder of said engine, a pipe for delivering a hydrocarbon agent from said main carbureter to said auxiliary carbureter shell, an air injector submerged in the explosive agent contents of said shell, a pipe for conducting air under pressure to said injector, a valve in said explosive agent conducting pipe, a valve in said air delivery pipe, and means for operating said valves in unison whereby one of said valves is always closed when the other valve is opened.

3. The combination with an explosive engine having a manifold for the delivery of explosive mixture, a main carbureter, a main conducting pipe leading to said manifold, a check valve for controlling communication between said main pipe and said manifold, an auxiliary carbureter shell, means for delivering air into said auxiliary shell to produce an explosive mixture, a pipe leading from said auxiliary shell to said manifold, said last named pipe having associated with it a member by which the explosive mixture passing to the manifold from the said pipe is directed against said check valve to close communication between the main carbureter pipe and the manifold.

4. The combination with an explosive engine having a manifold for the delivery of explosive mixture, a main carbureter, a main conducting pipe leading to said manifold, a check valve for controlling communication between said main pipe and said manifold,

an auxiliary carbureter shell, means for delivering air into said auxiliary shell to produce an explosive mixture, a pipe leading from said auxiliary shell to said manifold, 5 and a nozzle in said manifold directed toward said check valve into which explosive mixture is delivered from the pipe leading

from said auxiliary carbureter shell to press the valve to its seat.

STEPHEN S. KRAYER.
